UNITED STATES PATENT OFFICE.

ISIDOR NEUBURGER, OF NEW YORK, N. Y.

SHOW-CARD FOR EMBROIDERY.

SPECIFICATION forming part of Letters Patent No. 332,102, dated December 8, 1885.

Application filed April 2, 1884. Serial No. 126,405. (No model.)

To all whom it may concern:

Be it known that I, ISIDOR NEUBURGER, a citizen of the United States, residing at New York, in the county and State of New York, 5 have invented new and useful Improvements in Show-Cards for Embroidery and other Goods, of which the following is a specification.

My invention relates to improvements in devices for putting up embroidery, laces, and 10 similar goods; and it consists in a portfolio made of three connected sheets or flaps of pasteboard or other suitable material—namely, of an inner flap upon which the goods are wound, an outer recessed flap or cover, in 15 which recess or recesses the sample end is placed so as to be exhibited on the outside, and a bottom flap, the upper and lower flaps inclosing and protecting the goods wound upon the inner or middle flap.

20 In the accompanying drawings, Figure 1 is a perspective view of the portfolio without the lace or embroidery; Fig. 2, the same with the goods upon it; and Fig. 3, a top view of the cover, showing the sample end of the goods in 25 the recessed part of the same.

Similar letters refer to similar parts throughout the several views.

30 A is the inner flap, B the outer flap or cover, and C the lower flap. The three flaps A, B, and C are flexibly connected or hinged on the line *a b*, so as to fold together and accommodate themselves to the ordinary thickness of the goods wound upon the middle flap, A. The inner flap, A, may be made shorter than the

outer flaps; but by preference it is notched, as 35 shown in the drawings at *c d e f* and *g h i k*. The outer flap, B, is by preference recessed by providing it with slits *l* and *m*, through which the sample end of the goods is passed, so as to exhibit it on the outside of the cover; but, instead of recessing the outer flap by slitting it 40 in this manner, I may provide the end edges of the flap with recesses the same as those in the middle flap, A, as in dotted lines, Fig. 1.

When the portfolio is closed, the goods are 45 well protected and the sample end is exhibited upon the top or outside.

If desired, the portfolio may be inclosed within a box or case, as in my Letters Patent No. 231,346; but such constitutes no essential 50 feature of the present invention.

Having thus described my invention, what I claim is—

A show-card for exhibiting embroidery and other goods, consisting of three hinged sheets, 55 A, B, and C, two of which constitute covers for the other sheet, on which the goods are wound, and one of the cover-sheets being recessed at two points for exhibiting the end portion of the goods, substantially as described. 60

In testimony whereof I have hereunto set my hand in the presence of two subscribing witnesses.

ISIDOR NEUBURGER.
